CLAIM

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view showing the pattern design in FIG. 4.

The dot-dash broken lines in FIGS. 4 and 9 are for the purpose of illustrating the partially enlarged view and form no part of the claimed design. The broken lines, and unshaded surfaces bounded by broken lines, depict parts of the article's appearance that form no part of the claimed design.
